Primary Examiner — Michael A. Pratt*Assistant Examiner* — Wendy L Arminio(74) *Attorney, Agent, or Firm* — Baker & Hostetler LLP(57) **CLAIM**

The ornamental design for an overcap for a container closure, as shown and described.

DESCRIPTION

FIG. 1 is a top plan view of an overcap for a container closure showing my new design;

FIG. 2 is a partial cross-sectional right side view thereof taken in the direction of line 2-2 in FIG. 1;

FIG. 3 is an underplan view thereof;

FIG. 4 is a front view thereof;

FIG. 5 is a right side view thereof;

FIG. 6 is a rear view thereof;

FIG. 7 is a left side view thereof; and,

FIG. 8 is a cross-sectional view drawn to a larger scale, illustrating an in use engagement between a portion of the overcap for a container closure of FIG. 1 and a container closure drawn in broken lines.

The broken lines in FIG. 8 illustrating a container closure depict environment and form no part of the claimed design. All other broken lines depict portions of the overcap for a container closure that form no part of the claimed design.
